DESIGN FOR A FONT OF TYPE

Solomon S. Richmond, Malden, Mass., assignor to Beacon Products Corporation, Boston, Mass.,
a corporation of Massachusetts

Application June 14, 1946, Serial No. 130,686

Term of patent 14 years

(Cl. D64—12)

To all whom it may concern:

Be it known that I, Solomon S. Richmond, a citizen of the United States, residing at Malden, in the county of Middlesex and State of Massachusetts, have invented a new, original, and ornamental Design for a Font of Type, of which the following is a specification, reference being had to the accompanying drawing, forming part thereof.

The drawing illustrates front perspective views of a font of type, the backs of which have the same surface appearance as the front.

I claim:

The ornamental design for a font of type, as shown and described.
